UNITED STATES PATENT OFFICE.

GUSTAVE STICKLEY, OF SYRACUSE, NEW YORK.

DESIGN FOR A CHAIR-FRAME.

No. 37,503.

Specification for Design.

Patented Aug. 8, 1905.

Application filed June 26, 1905. Serial No. 267,150. Term of patent 7 years.

To all whom it may concern:

Be it known that I, GUSTAVE STICKLEY, a citizen of the United States, residing in the city of Syracuse, county of Onondaga, and State of New York, have invented a new, original, and ornamental Design for a Chair-Frame, of which the following is a specification, reference being had to the accompanying drawing, in which I show the chair-frame in isometric perspective.

I claim—

The ornamental design for a chair-frame, as shown.

GUSTAVE STICKLEY.
